PRINTING PRESS

Leroy Q. Presby, Melrose, Mass., assignor to American Stay Company, East Boston, Mass., a corporation of Massachusetts

Application May 21, 1938, Serial No. 209,284

18 Claims. (CL 101—247)

My invention relates to printing presses and is particularly concerned with means for holding the rolls of printing couples in cooperating relation and throwing them out of such relation.

5 The invention will be best understood from the following description when read in the light of the accompanying drawings of an embodiment of the invention, the scope of which latter will be more particularly pointed out in the appended claims.

In the drawings,

Fig. 1 is an elevation of a press constructed according to the invention with parts omitted;

15 Fig. 2 is a section on the line 2—2 of Fig. 1 with parts in elevation;

Fig. 3 shows a detail on an enlarged scale, and corresponds to a section on the line 2—2 of Fig. 1;

Fig. 4 is a section on the line 4—4 of Fig. 2;

20 Fig. 5 is a section on the line 5—5 of Fig. 3; and

Fig. 6 is a section on the line 6—6 of Fig. 5.

Referring to the drawings, the press illustrated has side frames 1 carrying bearings 3 for the shaft 5 of a printing cylinder 7, which cylinder 25 may be of the rotogravure type. Herein, the cylinder 7 is fixed to the shaft 5, and the latter is driven from a drive shaft 9 through a train of gearing, which gearing is indicated in its entirety by the reference character 11.

30 Cooperating with the printing cylinder 7 is an impression cylinder, which as illustrated comprises a body portion 13 carrying an outer layer of flexible material 15 such as rubber. Herein, the impression cylinder is mounted for rotation 35 on the relatively stationary shaft 17, longitudinal movement of the impression cylinder relative to the shaft being prevented by collars 19 releasably fixed to the shaft.

As illustrated, the shaft 17 for the impression cylinder is carried at opposite ends thereof by swinging arms 21, the shaft being connected to the free ends of the arms, while the opposite ends of the arms are pivoted at 23 to the adjacent side members 1 of the frame of the press. As 45 shown, the openings in the ends of the arms 21 which receive the ends of the shaft 17 are flared or "belled" from the center portion of the length of the opening toward the opposite ends of the opening as indicated at 25, which permits the 50 shaft slightly to rock or have slight universal movement relative to each arm. As shown, the arms are split as indicated at 27 from the opening which receives the shaft to the adjacent end of the arm. Through the split portion is passed 55 a bolt 29 which when tightened acts to clamp the

shaft in the opening of the arm without preventing the slight universal movement just mentioned. By this construction, by loosening the set screws 31, which hold the collars 19 in place, so that the collars may be slid along the shaft, 5 and loosening the bolts 29, the shaft 17 may be readily withdrawn and new impression rolls inserted.

As illustrated, extending across the top of the frame from one frame member 1 to the other is 10 a rigid girder 33, at one side of which projects a pair of spaced lugs 35 serving as bearings for a rock shaft 37, the latter at opposite ends being also journaled as indicated at 39 in the frame members. Mounted on the shaft 37 for sliding 15 and rotation thereon is a block 41 having an opening 43 in which is slidably mounted an elongated sleeve 45. Fixedly carried by the sleeve 45 at each of opposite ends thereof is a head 47. Sidely extending through the sleeve and its 20 heads is an elongated screw-threaded rod 49 to the lower end of which is fixedly secured a head 51 having a T-slot 53 through which slidably extends a bar 55, the latter at its medial portion being provided at each of opposite sides thereof 25 with longitudinally extending rib 57 giving that portion of the bar a T-shaped cross-section for fitting the T-shaped slot in the head 51.

At each of opposite sides of the block 41 the rock shaft 37 has splined thereon a perforated 30 boss 59 integrally formed with one end of an arm 61. The shaft for this purpose has a longitudinally extending key-way 63, Figs. 5 and 6, which receives a key 65 of length corresponding to the length of the hub 59. As shown, each hub 59 is provided with a set screw 67 acting on the key whereby each hub 59 may be releasably secured to the rock shaft 37. It will be observed from the construction described that when the set screws 67 are loosened the hubs 59 and the block 41 may be slid along the rock shaft into any desired adjusted position between the bearings 35 for the rock shaft, and that the screw-threaded rod 49 and the head 51 thereof will slide with them.

As illustrated, the head 47 at the lower end of the sleeve 45 is provided at one side thereof with a perforated boss 69 through which extends a pin 71 which projects at opposite ends from opposite sides of the head, as clearly indicated in 50 Fig. 1. Pivoted to each of these projecting ends of the pin 71 is the lower end of an arm 73. The lower ends of the two arms 61 and the upper ends of the two arms 73 are pivotally connected by a single pin 75. The arms 61 and 73 form tog- 55

gle levers which are just past the dead center with the pin 75 resting against the sleeve 45 as a stop, when the parts are in their positions shown by Fig. 3. Below the lower head 47 in contact therewith is a nut 77 screw-threaded on the rod 49. The toggle, therefore, when the parts are in their positions shown by Fig. 3, acts to press the rod 49 downward and press the impression cylinder into contact with the printing cylinder.

The opening 79 in each arm 21 for receiving the end of the bar 55 preferably is belled in opposite directions similarly to the openings in the arm 21 which receives the ends of the impression cylinder shaft 17, the bar at each end having a reduced cylindrical portion 81 received in the adjacent opening 79. By reason of this construction the impression cylinder may properly align with the printing cylinder to compensate, for example, for a printing cylinder or impression cylinder which is of slightly different diameter at one end than at the other. By adjusting the toggle mechanism lengthwise of the shaft 37 pressure may be applied by the toggle to the bar 55 at selected points longitudinally thereof, and by such adjustment the same pressure may be had at each end of the impression cylinder.

As illustrated, between the block 41 and the upper head 47 of the sleeve 45 is interposed a compression spring 83 which acts to urge the sleeve upwardly relatively to the block 41. Above the upper head 47 and in contact therewith the rod 49 carries a second nut 85 for transmitting the effort of the spring to the rod. This spring is preferably of such strength and under such tension that it just counterbalances the weight of the impression cylinder and the parts connected thereto, so that when the toggle is "broken," as hereinafter explained, the impression cylinder may be moved upwardly and will remain stationary in any position. However, the spring, if desired, may be of such strength as to raise the impression cylinder entirely away from the web when the toggle is broken.

45 As shown, the rock shaft 37 is provided at one end with a handle lever 87 by means of which the rock shaft may be turned to move the pin 75 of the toggle in the direction of the arrow shown in Fig. 3, and immediately upon the pin 50 passing over said dead center the pressure of the impression cylinder on the web passing between that cylinder and the printing cylinder will be relieved. By moving the handle lever in the opposite direction, when the toggle is broken, the pressure on the web will be reestablished.

Where a plurality of printing couples is employed the rock shaft 37 at its end opposite the handle lever 87 may be fixed thereto a lever 89 the lower end of which may be connected by a link 91 to similar arms 89 on other rock shafts 37 associated with other printing couples, so that when the handle lever 87 associated with one printing couple is operated to actuate the toggle associated with that printing couple the toggles associated with the other printing couples also will be actuated.

It will be understood that when the toggle is broken the impression cylinder may be moved high enough out of the way of the printing cylinder to permit the latter to be readily removed from its bearings. When a printing cylinder or impression cylinder of different diameter is substituted obviously the rod 49 must be moved up or down. This movement is permitted by screw-

ing the nuts 77 and 85 along the rod in the appropriate direction.

It will be understood that within the scope of the appended claims wide deviations may be made from the form of the invention above described without departing from the spirit of the invention.

I claim:

1. A printing press having, in combination, a printing cylinder, a cooperating impression cylinder, one of said cylinders having a shaft which is movable toward and away from the other cylinder, a single means for applying pressure to said shaft at points adjacent each end respectively of the cylinder which it carries for urging said cylinder toward the other cylinder, said means having provision for adjustably dividing the pressure exerted thereby between said points of application of said pressure.

2. A printing press having, in combination, a cooperating printing cylinder and impression cylinder, one of which cylinders is mounted on spaced bearings movable transversely of the axis of the other cylinder, a part extending longitudinally of said cylinders operatively acting on said bearings for causing pressure to be exerted on said bearings, pressure exerting means operatively acting on said part between said bearings, which means is adjustable longitudinally of said cylinders for applying the pressure exerted thereby to said part at selected points therealong.

3. A printing press having, in combination, a cooperating printing cylinder and impression cylinder, a pair of spaced swinging arms carrying one of said cylinders, a member extending between said arms for holding the cylinder carried by said arms in operative relation to the other cylinder, and normally rigid pressure exerting means acting on said member intermediate said arms.

4. A printing press having, in combination, a cooperating printing cylinder and impression cylinder, a pair of spaced swinging arms carrying one of said cylinders, a member extending between said arms for holding the cylinder carried by said arms in operative relation to the other cylinder, and pressure exerting means acting on said member intermediate said arms, which pressure exerting means is adjustable relative to said member for applying pressure thereto at selected points along said member.

5. A printing press having, in combination, a cooperating printing cylinder and impression cylinder, a pair of spaced swinging arms, means having a universal connection to said arms carrying bearings for one of said cylinders, a member extending between said arms having a movable connection thereto, and pressure exerting means acting on said member for urging said arms to swing transversely of the axes of said cylinders.

6. A printing press having, in combination, a cooperating printing cylinder and impression cylinder, a pair of spaced swinging arms, means having a universal connection to said arms carrying bearings for one of said cylinders, a member extending between said arms having a movable connection thereto, and pressure exerting means acting on said member for urging said arms to swing transversely of the axes of said cylinders, which pressure exerting means is adjustable relative to said member for applying pressure thereto at selected points along said member.

7. A printing press having, in combination, a

cooperating printing cylinder and impression cylinder, a shaft carrying one of said cylinders, spaced separately mounted means movable transversely of the axis of said cylinders, which means 5 carries said shaft, a universal connection between said shaft and separately mounted means, a part extending from one of said separately mounted means to the other and having a universal connection with each, and means acting 10 on said part for holding said cylinders in operative relation.

8. A printing press having, in combination, a cooperating printing cylinder and impression cylinder, one of which has spaced bearings movable 15 toward and away from the axis of the other cylinder, a part having spaced portions for operatively acting on said bearings for exerting pressure thereon, and a releasable toggle acting on said part between said bearings for exerting pressure 20 thereon, which toggle is adjustable along said part for exerting pressure thereon at selected points along said part.

9. A printing press having, in combination, a cooperating printing cylinder and impression cylinder, means for moving one cylinder toward and away from the axis of the other cylinder comprising a rod operatively connected to one of said cylinders, a normally fixed abutment, a spring 25 acting between said abutment and rod, and a releasable toggle between said abutment and rod acting in opposition to said spring.

10. A printing press having, in combination, a cooperating printing cylinder and impression cylinder, bearings for one of said cylinders, means 30 for moving said bearings transversely of the axes of said cylinders comprising a part movable therewith, normally fixed abutment means, a spring acting between said part and abutment means for urging said bearings in one direction, and a releasable toggle acting between said part and abutment means for moving said part in a direction opposite to that in which it is urged by said spring.

11. A printing press having, in combination, a cooperating printing cylinder and impression cylinder, bearings for one of said cylinders, means for moving said bearings transversely of the axes of said cylinders comprising a part movable therewith, abutment means, a spring acting between said part and abutment means for urging said bearings in one direction, a releasable toggle acting between said part and abutment means for moving said part in a direction opposite to that in which it is urged by said spring, and means for adjusting said part bodily relative to said spring and said toggle.

12. A printing press having, in combination, a cooperating printing cylinder and impression cylinder, bearings for one of said cylinders, means 45 for moving said bearings transversely of the axes of said cylinders comprising a movable elongated part, a pair of abutments on said part in spaced relation, operatively stationary abutment means, a spring acting between said stationary abutment means and one of the abutments of

said pair, and a releasable toggle between said abutment means and the other abutment of said pair.

13. A press according to claim 12 in which said part is slidably mounted for longitudinal movement on said operatively stationary abutment means, and said abutments of said pair of abutments are carried by said part at opposite sides respectively of said stationary abutment means and are adjustable longitudinally of said part. 10

14. A printing press having, in combination, a cooperating printing cylinder and impression cylinder, bearings for one of said cylinders, means for moving said bearings transversely of the axes of said cylinders comprising a movable elongated 15 part, a pair of abutments on said part in fixed spaced relation to each other, operatively stationary abutment means, a spring acting between said stationary abutment means and one of the abutments of said pair, and a releasable toggle 20 between said abutment means and the other abutment of said pair.

15. A press according to claim 14 in which said part is slidably mounted for longitudinal movement on said operatively stationary abutment 25 means, and said abutments of said pair of abutments are carried by said part at opposite sides respectively of said stationary abutment means and are adjustable longitudinally of said part.

16. A printing press having, in combination, a cooperating printing cylinder and impression cylinder, pressure and throw-off means for said cylinders comprising an elongated rod operatively connected to one of them, a rocker shaft, a block 30 mounted on said shaft for relative sliding and rotation, said rod operatively being longitudinally slidably mounted on said block, an abutment member on said rod at each side of said block in spaced relation thereto, which members are adjustable along said rod, a spring between 35 said block and one of said members, a second block splined to said rocker shaft, and a releasable toggle strut between said second block and the other abutment member.

17. A printing press having, in combination, 45 a cooperating printing cylinder and impression cylinder, bearings for one of said cylinders, means for moving said bearings transversely of the axes of said cylinders comprising an elongated rod, a pair of spaced abutments adjustable as a unit along said rod, a rock shaft, a crank arm carried by said rock shaft, a toggle link connecting said crank arm to one of said abutments, guide means for said rod carried by 50 said rock shaft, and a compression spring between said guide means and the other of said abutments.

18. A printing press according to claim 17 in which the rod is connected to the bearings by 60 an elongated part; said rod, pair of abutments, crank arm, guide means and spring being adjustable as a unit along said rock shaft and elongated part.

LEROY Q. PRESBY. 65
